US0D1043690S

(12) **United States Design Patent** (10) **Patent No.:** **US D1,043,690 S**
(45) **Date of Patent:** **** Sep. 24, 2024**

(54) **USB HUB**

(71) Applicant: **SHENZHEN XINJULUN ELECTRONICS CO., LTD.**, Shenzhen (CN)

(72) Inventor: **Xiaohua Wu**, Longyan (CN)

(73) Assignee: **SHENZHEN XINJULUN ELECTRONICS CO., LTD.**, Shenzhen (CN)

(**) Term: **15 Years**

(21) Appl. No.: **29/857,721**

(22) Filed: **Oct. 25, 2022**

(30) **Foreign Application Priority Data**

Oct. 13, 2022 (EM) 009205180-0002

(57) **CLAIM**

The ornamental design for a USB hub, as shown and described.

DESCRIPTION

FIG. 1 is a front, right and top perspective view of a USB hub, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the USB hub that form no part of the claimed design.

1 Claim, 8 Drawing Sheets
